NEGLIGEE

Filed Sept. 27, 1937

FIG. 1.

FIG. 2.

INVENTOR

Ethel Eaton Stricker

UNITED STATES PATENT OFFICE

107,058

DESIGN FOR A NEGLIGEE

Ethel Eaton Stricker, New York, N. Y.

Application September 27, 1937, Serial No. 71,818

Term of patent 3½ years

To all whom it may concern:

Be it known that I, Ethel Eaton Stricker, a citizen of the United States of America, residing in New York city, in the Borough of Manhattan, county and State of New York, have invented a new, original, and ornamental Design for a Negligee, of which the following is a specification, reference being had to the accompanying drawing, forming part thereof, wherein,

I claim:

The ornamental design for a negligee, substantially as shown.

ETHEL EATON STRICKER.
